Primary Examiner — Robin V. Webster*Assistant Examiner* — Lavone D Tabor*(74) Attorney, Agent, or Firm* — Collard & Roe, P.C.**(57) CLAIM**

The ornamental design for a dental cleaning head, as shown and described.

DESCRIPTION

FIG. 1 is a front perspective view of a dental cleaning head; FIG. 2 is a back perspective view of the design as shown in FIG. 1; FIG. 3 is a back view of the design shown in FIG. 1; FIG. 4 is a front view of the design shown in FIG. 1; FIG. 5 is a right end view of the design based upon the orientation of FIG. 4; FIG. 6 is a left end view of the design based upon the orientation of FIG. 4; FIG. 7 is a side view of the design shown in FIG. 1; and FIG. 8 is an opposite side view of the design as shown in FIG. 1; FIG. 9 is a reduced, environmental, perspective view showing the dental cleaning head installed on a handle; FIG. 10 is an enlarged left end view of the design as shown in FIG. 9; FIG. 11 is an enlarged right end view of the design as shown in FIG. 9; FIG. 12 is a side view of the design as shown in FIG. 9; FIG. 13 is back view of the design as shown in FIG. 9; FIG. 14 is the side view opposite that shown in FIG. 12; and, FIG. 15 is a front view of the design, as shown in FIG. 9. The broken lines and the areas within the broken lines illustrate portions of the dental cleaning head and in the case of the handle, environmental structure of dental cleaning head that form no part of the claimed design.
